(57) **CLAIM**

The ornamental design for a patient support cart with mounting plate, as shown and described.

DESCRIPTION

FIG. 1 is a front perspective view of patient support cart with mounting plate, showing my new design;
 FIG. 2 is a front elevation view thereof;
 FIG. 3 is a back elevation view thereof;
 FIG. 4 is a right side elevation view thereof;
 FIG. 5 is a left side elevation view thereof;
 FIG. 6 is a top plan view thereof;
 FIG. 7 is a bottom plan view thereof; and,
 FIG. 8 is a front perspective view thereof, showing attached blood pumps and an oxygenator as environment.
 In the drawings, the broken lines are for the purpose of illustrating environment only and form no part of the claimed design.
